UNITED STATES PATENT OFFICE.

BENJAMIN F. BELLows, DECEASED, LATE OF CLEVELAND, OHIO, BY NELLIE E. BELLows, ADMINISTRATRIX, OF CLEVELAND, OHIO, ASSIGNOR TO ELECTRIC COMPOSITOR COMPANY, OF NEW YORK, N. Y., A CORPORATION OF NEW JERSEY.

SLUG-EJECTING MECHANISM FOR LINE-CASTING MACHINES.

1,250,419.

Specification of Letters Patent. Patented Dec. 18, 1917.

Application filed August 16, 1915. Serial No. 45,819.

To all whom it may concern:

Be it known that BENJAMIN F. BELLows, late a citizen of the United States and a resident of Cleveland, Ohio, now deceased, 5 did during his lifetime invent certain new and useful Improvements in Slug-Ejecting Mechanism for Line-Casting Machines, of which the following is a specification.

This invention is intended for use as part 10 of a line casting typographic machine,—that is to say, a machine by which type bars or slugs are cast in a mold slot whose front face is closed by an assembled line of matrices.

15 In machines of this character the type bars are pushed out of the mold slot and between trimming knives by an ejector blade which engages that edge of the type bar or slug which is the bottom edge when the slug 20 is in use.

Machines of this sort are adapted to use and do use molds having slots of different sizes. It is practically necessary that the 25 ejector blade shall pretty nearly fill the mold slot as it pushes the type bar out. It is further necessary to use, from time to time, a variety of ejector blades, which must vary as to width, and may vary as to thickness, so that the ejector in use shall always 30 correspond with the dimensions of the slot of the mold in use.

The object of this invention is to provide in a machine of this sort a plurality of one piece ejectors having blades suitable for use 35 at different times and with different molds, together with means whereby any ejector blade may be readily brought into operative relation with the mold and with the mechanism by which the selected ejector blade may 40 be operated.

The invention consists in the combination of parts shown in the drawing and hereinafter described and pointed out definitely in the appended claims.

45 In the drawing, Figure 1 is a front elevation of a mold disk and the ejector mechanism behind it,—the mold which will be in the ejecting position having been removed from the mold disk; Fig. 2 is a side elevation 50 of the present invention and some associated parts; Fig. 3 is a side elevation, and Fig. 4 is a front view of the ejector operating slide. Fig. 5 is a side elevation of an ejector and

the adjacent end of the ejector operating slide. Fig. 6 is a front elevation of the 55 swinging ejector magazine.

Referring to the parts by reference characters, A' represents a centrally pivoted mold disk to which a plurality of molds A are secured over openings a' in said mold disk. The mold A at the top of the mold disk as shown in Fig. 1 is in the casting position; that is to say, in the position to have the front side of the mold slot a closed by a line of matrices, and to have molten 60 metal injected into its rear side. The mold which fits in and over the hole a' in the mold disk just to the left of the upper mold in Fig. 1 would be in the ejecting position, that is, the position it would occupy in order 65 that the to-be-described ejector mechanism may push a slug forward out of the mold slot.

The mold disk may be turned by any suitable mechanism, which has nothing to do 75 with the present invention; and the mold disk may be adapted for adjustment so that any one of the molds secured thereto, in the ordinary operation of the machine, will be moved back and forth between the casting 80 and ejecting positions, as described. The mold disk as shown carries five molds, but it might carry any desired number; and the mold slots of the several molds may be of various sizes depending upon the character 85 of the work which the machine is temporarily equipped for doing. Because the mold disk carries five molds as shown, it is desirable that there should be five ejectors B each fitted to coöperate with one of these molds. 90 In the construction shown five of such ejectors are shown, and they are slidably mounted in an ejector magazine D which is pivotally suspended from the shaft F, which may be a shaft having other functions, or 95 a shaft especially provided for the purpose. Each ejector comprises a body b (and all of these bodies are preferably the same size) and a blade b' which is preferably formed integrally with the body, and projects forward therefrom. All of these blades are of the same length, but they vary in width and may vary in thickness, as required. Some may be narrower than the body, one the same width, and one or more may be wider. 100

105 The bodies b of these ejectors have parallel

top and bottom edges, and these are slidably mounted in guide grooves d in the upper and lower members of the ejector magazine. These ejectors, when so mounted, occupy 5 nearly parallel positions, although they actually occupy positions which are radial with respect to the axis about which said magazine may swing.

The ejector magazine may be swung into 10 positions to bring any desired blade into operative relation, that is to say, into alignment with the slot of that mold which is in the ejecting position. To so move the magazine a rocking sleeve G is mounted in suitable fixed bearings concentrically with the shaft F . This sleeve, at its rear end, is formed with an arm g that is pinned to the frame d^2 of the ejector magazine, whereby 15 the magazine must rock with said sleeve. 20 This sleeve also carries a handle g' by which it may be rocked; and is provided with a downwardly extended arm g^2 having near its lower end a hole through which the index pin K may pass. This arm g^2 passes between two parts n n' of the fixed frame of 25 the machine, and in these parts are five index holes n^2 . By putting the index pin in the proper holes n n' , and through the hole in the arm g^2 , the ejector magazine will be 30 fixed in the desired position.

When any ejector is in operative relation with the mold, it is likewise in operative 35 relation with the ejector operating slide M . This is mounted in dovetailed guideways so as to be movable forward and backward; and is associated with suitable mechanism, which may be substantially like that shown in Letters Patent No. 1,080,570. A part only of the mechanism shown in that patent is 40 shown in Fig. 2 of the drawing of this application, viz., a lever P having a pin p at its upper end; and a hook R which is pivoted to the slide M and engages said pin. The lever P is positively rocked backward 45 and forward, thereby moving said slide, by two cams T T' with which two arms p' p^2 respectively engage. A plate m which projects forward from and is rigidly fastened to the slide M has a T-shaped tenon m' 50 which may easily enter a T-shaped mortise b^3 in the rear end of the body part of each ejector. This slide M is so placed that said T-shaped tenon m' will be in the notch b^3 .

Copies of this patent may be obtained for five cents each, by addressing the "Commissioner of Patents, Washington, D. C."

of that one of the ejectors which is in operative position. This comes about in part 55 from the location of said slide, and in part because, as the ejector magazine is swung about its pivotal support, the T-shaped cross mortises in the several ejectors go over said T-shaped tenon, wherefore, when the ejector 60 magazine stops and is fixed in position, the T-shaped tenon m' is in the T-shaped mortise of that ejector which is in operative position with respect to the mold.

Having described the said invention, I 65 claim:

1. Ejector mechanism for typographic machines comprising, in combination, a mold, ejector operating mechanism which includes a guided slide adapted to engage 70 with any ejector which is brought into alignment with it, a pivoted ejector magazine located between said mold and ejector operating slide, a series of ejectors slidably mounted in said magazine,—said magazine 75 being capable of swinging to bring any ejector therein into operative relation with the mold and with the ejector operating slide.

2. Ejector mechanism for typographic 80 machines comprising, in combination, a mold, ejector operating mechanism which includes a guided slide adapted to engage with any ejector which is brought into alignment with it, a pivoted ejector magazine 85 located between said mold and ejector operating slide, a series of ejectors slidably mounted in said magazine,—said magazine being capable of swinging to bring any ejector therein into operative relation with 90 the mold and with the ejector operating slide, and means for locking said magazine in any operative position.

3. A slug ejecting mechanism for linotype 95 machines having a plurality of ejectors mounted on a common axis and adapted to selectively coöperate with the mold disk.

In testimony whereof, I hereunto affix my signature in the presence of two witnesses.

NELLIE E. BELLOWES,
Administratrix of the estate of Benjamin F. Bellowes.
